BASKETBALL GOAL

Elzie H. Procter, Rte. 3, Box 111, Elmwood, Ind.

Filed Mar. 3, 1965, Ser. No. 84,071

Term of patent 7 years

(Cl. D34—5)

Fig. 1.

Fig. 2.

Fig. 3.

FIG. 1 is a front elevation of a basketball goal showing my new design.

FIG. 2 is a side elevation of said goal.

FIG. 3 is a perspective view of said goal taken generally from the rear and slightly above the goal.

I claim:

The ornamental design for a basketball goal, as shown.
